UNITED STATES PATENT OFFICE

2,372,316

DUST COLLECTOR

Harold W. Curtis, Stoughton, Mass., assignor to
B. F. Sturtevant Company, Boston, Mass.

Application March 5, 1943, Serial No. 478,089

2 Claims. (Cl. 183—108)

This provision relates to dust collectors and has as an object the provision of a rugged, efficient collector which may be inserted at the inlet of an induced draft fan for removing dust entrained in the gas moved by the fan.

Cyclone type dust collectors are generally used for connection to the induced draft fans of, for example, steam power plants for removing cinders and fly ash from the flue gases. Such collectors are relatively expensive, and require more space than sometimes is available.

This invention provides a simple, rugged collector utilizing a minimum of apparatus having but a low draft loss and requiring less space than the usual collector.

The invention will now be described with reference to the drawing, of which:

Fig. 1 is a transverse section through a dust collector embodying this invention;

Fig. 2 is a sectional view with a portion cut away, along the lines 2—2 of Fig. 1, and

Fig. 3 is an enlarged sectional view of one of the nozzles and its associated tubes of Fig. 1.

The casing 5 has extending upwardly therefrom, the gas inlet duct 6, and has the dust hopper 7 extending downwardly therefrom in alignment with the duct 6.

The outlet duct 8 extends the width and depth of the casing, has its inner end connected thereto and extends therefrom for connection at its outer end as to an induced draft fan.

At the connection of the inlet duct 6 to the casing 5, the plate 9 extends therebetween and contains the plurality of converging nozzles 10. The cylindrical tubes 11 are mounted in the casing 5 below and in alignment with the nozzles, the interiors of the tubes 11 being substantially larger than the lower ends of the nozzles.

The plate 12 which supports the tubes 11 from the sides of the casing 5 and which separates the space within the casing around the tubes from the hopper, extends into the outlet duct 8 to overlap a portion of the lower wall 13 of the duct 8, forming a recirculated air passage 14 in which is mounted the adjustable damper 15.

As the gas and entrained dust from the inlet duct 6 passes through the nozzles 10, the velocity is increased and although the larger portion of the gas is drawn from the nozzles and around the exteriors of the tubes 11, the dust particles are given sufficient momentum to cause them to pass through the tubes 11 into the hopper 7.

The dust free gas from the hopper is drawn therefrom through the passage 14, past the

damper 15. The damper 15 is adjusted to provide sufficient suction through the passage to provide a slight negative pressure therein for facilitating the dust collection and for providing recirculation, yet insufficient to cause the dust particles from the hopper 7 to be drawn into the outlet duct.

While one embodiment of the invention has been described for the purpose of illustration, it should be understood that the invention is not limited to the exact apparatus and arrangement of apparatus illustrated as modifications therefrom may be suggested by those skilled in the art without departure from the essence of the invention.

What is claimed is:

1. A dust collector comprising a casing, a plurality of spaced, substantially vertically extending tubes in said casing, a dust hopper attached to said casing below said tubes, a substantially horizontal plate extending across said casing above said tubes, means forming a plurality of relatively small nozzles in said plate aligned with said tubes, an outlet duct having a substantially horizontal lower wall attached to said hopper and having a substantially horizontal upper wall attached to said plate, and a substantially horizontal partition extending across said casing above said lower wall of said duct, said partition having perforations therein through which said tubes extend, said partition and said lower wall forming a passage into said outlet duct for dust free gas from said hopper.

2. A dust collector comprising a casing, a plurality of spaced, substantially vertically extending tubes in said casing, a dust hopper attached to said casing below said tubes, a substantially horizontal plate extending across said casing above said tubes, means forming a plurality of relatively small nozzles in said plate aligned with said tubes, an outlet duct having a substantially horizontal lower wall attached to said hopper and having a substantially horizontal upper wall attached to said plate, a substantially horizontal partition extending across said casing above said lower wall of said duct, said partition having perforations therein through which said tubes extend, said partition having a portion extending into said duct overlapping said lower wall, and a damper between said portion of said partition and said lower wall, said partition and said lower wall forming a passage into said outlet duct for dust free gas from said hopper.

HAROLD W. CURTIS.
